(57) **CLAIM**

The ornamental design for an ultra-wideband dual polarization horn antenna, as shown and described.

DESCRIPTION

FIG. 1 is a perspective view of an ultra-wideband dual polarization horn antenna design showing my new design. FIG. 2 is a front view of an ultra-wideband dual polarization horn antenna.

FIG. 3 is a rear view of an ultra-wideband dual polarization horn antenna.

FIG. 4 is a left side view of an ultra-wideband dual polarization horn antenna.

FIG. 5 is a right side view of an ultra-wideband dual polarization horn antenna.

FIG. 6 is a top view of an ultra-wideband dual polarization horn antenna; and,

FIG. 7 is a bottom view of an ultra-wideband dual polarization horn antenna.

Any shading and cross-hatching are not features of the design but are utilized to illustrate the surface contours of the ultra-wideband dual polarization horn antenna design in the drawings.

The broken lines depict portions of the ultra-wideband dual polarization horn antenna that form no part of the claimed design.
